ROTARY SLIDE RULE

Arthur Liley, 766 Merriman Road, Akron, Ohio 44303

Continuation-in-part of abandoned design application Ser. No. 379,503, July 16, 1973. This application Sept. 16, 1975, Ser. No. 614,056

Term of patent 14 years

Int. Cl. D19—99

U.S. Cl. D64—11 B

FIG. 1

FIG. 2

FIG. 1 is a top perspective view of a rotary slide rule showing my new design, and

FIG. 2 is a bottom perspective view thereof.

This application is a continuation-in-part of my earlier application Ser. No. 379,503, filed July 16, 1973, now abandoned.

I claim:

The ornamental design for a rotary slide rule, as shown.
